Inventor,
Milton B. Ketcham.
By his Attorney.
Ramsay Hoguet.

UNITED STATES PATENT OFFICE.

MILTON B. KETCHAM, OF RIDGEWOOD, NEW JERSEY.

COMPOSITE LEATHER HEEL.

Application filed May 4, 1926. Serial No. 106,646.

My invention relates to improvements in heels for attachment to boots and shoes. The object of my invention is to produce a simple and durable heel which can be applied to a boot or shoe precisely like the ordinary heel and which is a cushion heel exceedingly comfortable to the wearer and combining the good qualities of leather and rubber.

10 Many wearers of cushion heels prefer a leather tread and many prefer the rubber. My improvement is intended to satisfy both classes of wearers.

15 The object of my invention is to produce a heel which will have a leather top lift, a rubber or cushion back for the top lift and with the rubber projecting through and anchored in the leather and disposed so as to make a series of rubber gripping surfaces near the edge portions of the top lift. I arrange these anchoring rubber parts so that the fastening nails go through them and in a manner to prevent the nail heads ever coming in contact with the ground.

20 Thus the rubber bosses or projections will give a sufficient gripping surface on slippery places when the ground is dry, the leather will take on such places when the ground is wet, and the backing will give 25 the desired cushioning effect.

My invention is further intended to have the leather and rubber components of my improved heel united in such a way that the parts cannot slip with relation to each other 30 and the slipping or sliding strain on the top lift is taken largely away from the fastening nails.

35 My invention is further intended to produce a heel which can be used in the usual way and which will have a better appearance than many heels now in use.

Reference is had to the accompanying drawings forming a part of this specification in which similar reference characters refer 40 to similar parts throughout the several views.

Figure 1 is a face view of the top lift forming a part of my invention;

Figure 2 is an inside view of the top lift, 50 and

Figure 3 is a section on the line 3—3 of Figure 2, but showing the top lift united with its cushion back.

The top lift 10 is made of sole leather 55 and is of the desired heel shape. It is united at its back with the cushion lift or

body 11 of rubber. The top lift is provided with a series of holes 12 located near the edge and these holes are countersunk and reamed out at the outer portion of the lift, 60 as shown at 13 and the fastening nails 14 go through the holes 12 and through that portion of the rubber which fills the holes.

In uniting the parts 10 and 11, they are put together under pressure when the rubber is plastic and before vulcanizing so that the rubber enters the holes 12 and fills the spaces 13, except for enough space to provide for the heads of the nails 14.

When heels have been made of rubber and leather heretofore, there has been a tendency for the top lift or leather part 10 to slide with relation to the part 11 and bring all the lateral strain on the fastening nails 14. To obviate this I provide a series of 70 recesses 15 in the back of the top lift 10 which are preferably arranged in crossing rows as in Figure 2, although they may be disposed in any desired manner. It will be seen that when the rubber and leather are 75 forced together as shown in Figure 3, the rubber will fill the recesses 15 and be anchored firmly therein and thus tend to better unite the parts 10 and 11 and to prevent any 80 slipping or sliding movements of said parts 85 with relation to each other.

The heel is attached to a base portion 17 of a shoe or boot precisely as usual by the nails 14 and it will be noted that the rubber from the cushion 11 which substantially fills 90 the holes 12 and 13, extends to the tread surface of the top lift and thus a row of these plugs or parts extend around the heel near the edge portion forming an excellent gripping and cushioning surface.

It will be noticed that as the top lift is 95 essentially of leather, it can be reinforced against wear either with slugs or otherwise, precisely like the ordinary leather heel.

I claim:

A composite cushion heel comprising a 100 leather top lift having holes therethrough near the edge, said holes being enlarged at their outer parts, and a rubber back or body for the top lift having the rubber extended 105 into and filling the aforesaid holes which are disposed to receive fastening nails.

In testimony whereof, I have signed my name to this specification this 30th day of April, 1926.

MILTON B. KETCHAM.
